DISPENSING DEVICE

Morris Miller, Detroit, Mich., assignor to Miller
Laundry Machinery Company, Detroit, Mich.,
a partnership

Application April 17, 1941, Serial No. 388,952

3 Claims. (Cl. 221—146)

This invention relates to a dispenser or storage and supply device, and in particular it relates to a storage device of the hopper type in combination with means for regulating the dispensing movement of stored material, and in combination with means positioning the hopper for filling same.

In commercial laundries it is customary to sort various fabrics either before or after the laundry is washed. One application of a use of the present device in commercial laundries is to sort towels after they are washed and dried. It is generally customary to provide a relatively large table or bench upon which piles of towels are assembled. From this pile the operator removes the towels one by one, inspects them, and either stacks them to form a bundle or sets them aside to be further treated. Sorting towels in this manner usually requires relatively large tables which occupy valuable floor area. Furthermore, the towels, when placed in a pile on the table, usually become scattered, making it both difficult for the operator to reach the towels, and increasing the amount of manual labor.

According to my invention I provide a device in the form of a hopper which may be inclined to a position so that one of the principal sides of the hopper rests in a horizontal plane at table top level. Into this hopper may be piled a substantial quantity of towels amounting to several hundred pounds. When so filled the hopper may be elevated manually to an upright position assisted by counterweights. The lower end of the hopper is spaced from the top of a table onto which the towels drop into an accessible position from which the operator may conveniently withdraw the towels, sort them, inspect them, or stack them in bundles.

Among the objects of my invention are to provide in combination a device which is capable of positioning towels in a readily accessible position for the operator; to provide a device which will support a substantial quantity of towels; to provide a device which will retain a substantial quantity of towels and at the same time occupy a minimum floor area; to provide a supply device of the hopper type from which towels may be easily removed therefrom, and to provide a towel supply device which is easy to fill, simple in operation and economical to manufacture.

These and other objects and advantages will appear more fully in the following description when considered in connection with the accompanying drawing in which:

Figure 1 is a perspective view of a towel supply 55 panel 26 provided with hinges 27 attached to the

device representing an embodiment of my invention;

Figure 2 is a rear elevational view thereof;

Figure 3 is a side view, in section, taken along lines 5—5 of Figure 1 and illustrating a hopper associated therewith in lowered position; and,

Figure 4 is a side view, in section, taken along lines 5—5 of Figure 1 and illustrating a hopper associated therewith in its normal upright position.

Referring to the drawing and in particular to Figure 1, I show an embodiment of my invention which includes a structural frame 6 in a rectangular formation serving as a table and provided with a plate 7 forming the table top. Side plates 8 and 9 attached to the structural frame-work 6 serve as enclosures for the sides of the table structure. A vertically disposed plate 10 interposed between the end plates 8 and 9 functions as a partition while a bottom plate 11 and back plate 12 (Fig. 2) complete the enclosure. As thus described, the plates and frame work constitute a table-like structure having two enclosed bins open at the front end of the table structure.

These bins merely serve as repositories for materials which are sorted on top of the table structure.

A pair of vertical angles 13 and 14 extend upward from the rear edge of the table structure and are connected together at their upper ends by a horizontal member 15. Gusset plates 16 are attached at the corners of the structural members for increasing the rigidity of the assembly. A structural angle 17 is positioned in a horizontal plane above the top of the table 7 and is attached to the vertical members 13 and 14. A back plate 18 fills in the gap between the angle 17 and the top of the table plate 7.

To the horizontal angle 17 is attached a hopper 19 by means of a pair of hinges 20. When the hopper is in its upright position its back surface lies in a vertical plane in line with the back edge of the table. The width of the hopper is slightly less than the total width of the table.

The hopper is maintained in its normal upright position by means of counterweights 21 attached to the hopper by cables 22 operated over pulleys 23 supported by brackets 24 attached to the horizontal member 15. Tubular guards 25 are provided within which the counterweights 21 are vertically movable. These guards 25 are held in place by brackets 34 attached to the main structural frame 6.

The lower end of the hopper is open, and a panel 26 provided with hinges 27 attached to the

front surface of the hopper 19 provides means for varying the size of the opening at the lower end of the hopper. The panel 26 forms in effect a movable portion of the front surface of the hopper at the lower end of the hopper. To limit the outward movement of the panel 26, chains 28 attached to the sides of the hopper 19 are engageable with hook members 29 extending from the panel 26. The chain provides means which will limit outward movement of the panel 26, but will allow the panel to move into the same plane as the front surface of the hopper.

In order to swing the hopper into its lowered position, a handle 30 is provided which connects with the upper portion of the hopper through a heavy cord 31 and a bracket 32. Side guards 33 extend vertically from the table top 7 and at the sides of the table to prevent materials, which drop through the hopper opening, from flowing over the sides of the table. These plates 33 are spaced apart a sufficient distance so that the hopper may pass therebetween when it is swung into its lowered position.

In the operation of the device, and as shown in Fig. 3, the operator pulls the hopper to its lowered position at which point it offsets the weight of the counterbalance weights 21. While in this convenient position the operator fills the hopper with fabric materials, such as towels 35. Thereafter the operator pushes the hopper to the upright position as shown in Figure 4, whereupon the towels drop through the lower opening of the hopper onto the table top 7 and in a readily accessible position for withdrawal by the operator.

As shown in Figure 4, the opening at the lower end of the hopper is greater than the distance from the top of the table to the bottom of the hopper whereat the hopper is hinged. It has been found this relationship is desirable for the proper outlet distribution of the towels. While ordinarily such a relationship would prevent the hopper from being lowered to the position as shown in Figure 3, the fact that the panel 26 is freely movable so that it may be aligned in the same plane as the front surface of the hopper permits the hopper to be lowered to the position illustrated. As the hopper is brought to its lowered position the panel 26 engages the table top 7 and moves automatically in alignment with the front surface of the hopper.

From the foregoing it is believed apparent that I have provided a novel and useful device for increasing the efficiency in commercial laundries, and while I have shown and described a preferred embodiment of my invention it is to be understood that it is susceptible of those modifications which appear within the spirit of my invention and the scope of the appended claims.

Having thus described my invention what I claim and desire to protect by Letters Patent is:

1. In a device of the character described in combination, a structural frame including a table top, a hopper positioned above the table top and in spaced relation therefrom, structural members forming a vertical continuation of the table top at the rear of the table top, hinged means connecting the lower end of the hopper

with the continuation structural members at an elevation so that the front surface of the hopper will lie in close parallel relation with the plane of the table top, said hopper having an opening at the bottom thereof, and a hinged panel forming a part of the front wall of the hopper adjacent the bottom opening, the distance between the bottom of the hopper and the top of the table being such that upon lowering the hopper to a horizontal position the said hinged panel strikes the table top and is moved into alignment with the front surface of the hopper wall, the transverse width of said opening being greater than the distance between the table top and the bottom of the hopper.

2. In a device of the character described in combination, a structural frame including a table top, a hopper positioned above the table top and in spaced relation therefrom, structural members forming a vertical continuation of the table top at the rear of the table top, hinged means connecting the lower end of the hopper with the continuation structural members at an elevation so that the front surface of the hopper will lie in close parallel relation with the plane of the table top, said hopper having an opening at the bottom thereof, a hinged panel forming a part of the front wall of the hopper adjacent the bottom opening, and means for limiting the outward movement of the panel while the panel is freely movable so that the same will lie in the plane of the front surface of the hopper, the distance between the bottom of the hopper and the top of the table being such that upon lowering the hopper to a horizontal position the said hinged panel strikes the table top and is moved into alignment with the front surface of the hopper wall, the transverse width of said opening being greater than the distance between the table top and the bottom of the hopper.

3. In a device of the character described in combination, a structural frame including a table top, a hopper positioned above the table top and in spaced relation therefrom, structural members forming a vertical continuation of the table top at the rear of the table top, hinged means connecting the lower end of the hopper with the continuation structural members at an elevation so that the front surface of the hopper will lie in close parallel relation with the plane of the table top, said hopper having an opening at the bottom thereof, a hinged panel forming a part of the front wall of the hopper adjacent the bottom opening, and counterbalancing means of sufficient weight to maintain the hopper in a normal vertical position but of insufficient weight to overcome the weight of the hopper when the hopper is moved to a horizontal position, the distance between the bottom of the hopper and the top of the table being such that upon lowering the hopper to a horizontal position the said hinged panel strikes the table top and is moved into alignment with the front surface of the hopper wall, the transverse width of said opening being greater than the distance between the table top and the bottom of the hopper.

MORRIS MILLER.
